UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,634, dated September 11, 1894.

Application filed August 3, 1894. Serial No. 519,871. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornaments formed of cornucopia-like scrolls with roses 10 and leaves, arranged at uniform distances apart between narrow vertical stripes as represented in the accompanying drawing.

The border or upper portion of the design is formed of ornamental scrolls with roses and leaves as shown in the drawing.

What I claim is—

The design for wall paper herein shown and described.

Witness my hand this 31st day of July, 1894.

CHARLES BOOZE.
